METHOD OF AND APPARATUS FOR AIR LIQUEFACTION

Filed June 1, 1925

INVENTOR

Isaac H. Levin

UNITED STATES PATENT OFFICE

ISAAC H. LEVIN, OF PITTSBURGH, PENNSYLVANIA, ASSIGNOR, BY MESNE ASSIGNMENTS, TO GAS INDUSTRIES COMPANY, OF PITTSBURGH, PENNSYLVANIA, A CORPORATION OF PENNSYLVANIA

METHOD OF AND APPARATUS FOR AIR LIQUEFACTION

Application filed June 1, 1925. Serial No. 34,071.

The invention relates to method and apparatus for the transfer of heat between fluids and the purification of fluids as is commonly required in the production of liquid air and related processes. In such processes, some of the constituents of the fluids during the heat transfer process may become congealed on the heat transfer surfaces. The fluid is thus purified but the heat transfer may be impaired if not completely stopped by reason of blockage or by the lowering of the coefficient of heat transmission.

The operations of heat transfer and of purification are therefore opposing ones and the invention has therefore for its special object a method and apparatus to carry out the method whereby both the heat transfer and the purification can be carried on efficiently. Some of the specific objects contributive to this end are herein mentioned.

The object of this invention is to enable one to build an interchanger of light weight and construction and thus minimize the loss of energy required to cool the mass of the interchanger.

Another object is to reduce the manufacturing cost of the apparatus.

A further object is to enable one to construct an interchanger which shall require the simplest piping for interconnecting the interchanger with the rest of the apparatus. A further object is to enable one to operate an interchanger with the end that is at room temperature facing downward.

A further object is to enable one to attain the above objectives and at the same time have an interchanger that will operate through long periods of time without clogging and thus avoid the necessity of frequent shutdowns and defrosting of the interchanger.

Another object is to build an interchanger with many paths in parallel instead of a few paths in series. Another object is to build an interchanger that will maintain its efficiency as measured by the difference in temperature between the incoming and outgoing fluids over long periods of operation.

The invention can be readily understood by referring to the accompanying drawing which embodies a device for carrying out the

same. A jacket 5 is fastened to tube sheets 1 placed at the top and bottom of the interchanger. Tubes 3 are fastened to the tube sheets. A head 2 is attached to top tube sheet and forms with it the space 15. A head 6 is attached to the bottom tube sheet and forms with it the space 13. The fluid may enter the interchanger at 8 pass thru distributor pipes 12 and then up the tubes 3 thru the nozzles 4 and out thru the opening 9. Another fluid may enter opening 10 pass over the baffles 14 and then out thru the opening 11. No specific method for fastening the jacket to the tube sheet or the tubes to the tube sheets are herein given as this will vary with the different fluids used and the temperature and pressure of same. The nozzles 4 may be separate units distinct from the tubes but fastened to same or they may be formed by constrictions in the tubes depending upon the specific nature and condition of the fluids handled.

The distributor 12 is here shown as a number of pipes spread out spider fashion from the inlet pipe 8. There are, however, many other means to distribute the fluid entering 8 so that the fluid may not be crowded up thru only some of the pipes 3. The specific device or scheme used to obtain a distribution of the fluids thru the pipes 3 may likewise depend upon the specific conditions of the fluids treated.

The interchanger shows only two streams in heat transfer relation, but the interchanger can be used to handle several streams (not shown) in similar relation to one another instead of the two streams herein described.

A good example of the application of this invention is to the production of oxygen by the air liquefaction process. Air under pressure is sent into tube 8 and is distributed in the space 13 and then passes up tubes 3, thru the nozzles 4 and into the space 15 and then thru outlet 9 into the fractionating column.

The air is treated in the column and separated into its constituents. The nitrogen and oxygen and the other gases leave the column at the very low temperatures.

For the sake of making clear the operations that take place in the interchanger let us assume that only the nitrogen passes into the

interchanger shown and that the oxygen passes in heat transfer relation with a portion of the air in still another interchanger. The cold nitrogen enters at 10 passes over the baffles 14 and leaves at 11. The air enters at 5 the bottom of the interchanger at about room temperature and leaves the top of the interchanger at very low temperatures. The air is as a rule treated while under pressure before it enters the interchanger so that it is 10 free from carbon dioxide and moisture to the extent that can be brought about by agents such as caustic soda or caustic potash.

The temperature of the air at the exit of 15 the interchanger is sufficiently low to precipitate practically all of the water and carbon dioxide. The nitrogen as it passes downwardly thru the interchanger gradually becomes warmer so that it leaves at 11 at about 20 the temperature of the incoming air.

As the air becomes progressively colder frost and carbon dioxide snow tend to deposit out and thus purify the air, while at the same time the heat transmission coefficient becomes 25 reduced and actually pipe blockage may occur if provisions are not taken to give to the ascending air large passages for the deposits to form. The deposits start at about $\frac{1}{3}$ or so from the top of the interchanger and as more 30 deposits form this cold region descends until it gets down to too low a point for efficient heat transfer; the difference in temperature between the nitrogen and the air increases and too much heat is lost, and the operation 35 of the column ceases to function properly.

If an interchanger as described but without the nozzles 4 or the equivalent for same and without the distributor were to be used the interchanger would not function, that is, 40 the stream of nitrogen would not heat transfer with the stream of air and the temperature difference between the air and the nitrogen would very rapidly become greater and greater.

45 Prior to my invention it was well known in the art that an ordinary tubular interchanger would give the dire results just described. Reference to this phenomena is given for example in U. S. Patent 1,323,014 50 by G. Claude. The reason that results can not be obtained is that the air as it gets colder gets heavier and convection currents are set up resulting in the cold air dropping to the bottom or warm end of the interchanger.

55 Eddy currents are set up and the temperature gradient from top to bottom of the interchanger can not be maintained and the interchanger ceases to function properly. While a lack of uniformity in the flow of air in the 60 tubes 3 exaggerates the adverse operating conditions, nevertheless perfect distribution does not entirely eliminate the eddy currents.

On the other hand the effect of the nozzles 65 on the flow of the air in the tubes eliminates the eddy currents and permits the successful

use of the interchanger. The use of the nozzles 4 permit the use of larger size tubes 3 than is required for heat transfer and without appreciable loss in the over all heat transmission coefficient. This extra room in the 70 tubes permits the accumulation of frost over long periods of time without clogging and also permits a saving in chemicals in the preliminary purification of the air.

It can now easily be seen how by the use 75 of the novel features described by this invention the various objects set forth can be obtained and how very efficient and economical construction and operation for heat transfer and purification of fluids can be attained.

The use of the invention is not limited to 80 an interchanger in the position herein shown and described. While only one nozzle 4 per tube 3 is described, the invention is not limited to only one, as several may be used in 85 series.

The use of the word "nozzle" is not to be construed to be limited to just a nozzle, but to cover any scheme that will cause an increase in the velocity of the fluid in a portion 90 of the tube or increase the differential pressure across portions of the tube.

The application of the invention is not limited to the examples of the use herein described but can be applied in various other 95 ways to the art mentioned and to other arts where heat transfer is required.

I claim:

1. In a heat interchanger, fluid conducting tubes within the interchanger for the upward flow of fluids through the same, a restriction within each tube placed in sections of the tubes near the tops and beyond the entrance thereof to increase the pressure drops in said sections of the tubes, and means 100 adjacent the reduced portions of the tubes for introducing a separately confined downwardly flowing fluid to the interchanger.

2. In a heat interchanger for air liquefaction, means for introducing air into the bottom thereof, a vertically extending air conducting member having means disposed near its upper end only for increasing the velocity of the air passing therethrough, said conductor member throughout its remaining portion having an unrestricted passage, and means adjacent the velocity increasing means for introducing a separately confined downwardly flowing fluid to the interchanger.

3. In a heat interchanger having an outer shell, a lower fluid receiving chamber, an upper fluid discharge chamber, fluid conducting tubes in communication with the lower and upper chambers, means for increasing the velocity of the fluid while it is passing 125 through the upper portions of the tubes, said means disposed beyond the entrance ends of the tubes and in proximity with the upper chamber, means disposed adjacent to the velocity increasing means for introducing a 130

separately confined cooling fluid to the interchanger, and means for passing the cooling fluid through the interchanger in an opposite direction from the fluid passing through the tubes.

4. The method of transferring heat between fluids and the products resulting from the fractional distillation of same, which consist in causing a plurality of parallel streams of a fluid to be passed in one direction and increasing the velocity of the fluid streams at the end of their passage to prevent convection currents acting on the fluid streams, and simultaneously passing a stream 10 of a product resulting from the fractional distillation in an opposite direction and in thermal contact with the said first fluid streams, said introduction of said product being effected at the point of increased velocity.

5. The method of transferring heat between fluids and the products resulting from the fractional distillation of same, which consists in passing one fluid through a plurality of parallel paths in an evenly distributed volume throughout the paths, increasing the velocity of the fluids in said paths at points near the termination thereof, introducing a second fluid stream into thermal contact with the first stream at points adjacent the said terminations, and simultaneously passing said second fluid stream in an opposite direction and in thermal contact with said first stream.

35 6. In an interchanger for air liquefaction having an outer shell, a relatively warm lower air admission chamber, a relatively cold upper discharge chamber, a series of vertically extending flues arranged in parallel connecting the said chambers, restrictions in said flues located near the upper chamber, and means for passing a fluid downwardly and in thermal contact with the upwardly passing air, said latter means including a separately confined outer shell fluid admission port disposed adjacent the said restrictions and at the upper end of the interchanger, a fluid discharge port at the lower end of the interchanger, and a series of baffles disposed between the said 40 ports.

50 7. In a heat interchanger, a fluid conducting tube located within the interchanger, means associated with the tube for effecting an upward flow of fluid through the tube, a restriction within the tube positioned near the top and beyond the entrance end thereof to increase the velocity of the fluid while it is passing through the upper portion of the tube, and means adjacent the reduced portion 55 of the tube for introducing a separately confined downwardly flowing fluid to the interchanger.

In testimony whereof I affix my signature.
